UNITED STATES PATENT OFFICE.

JOHN FRITZ, OF BUFFALO, NEW YORK.

DESIGN FOR A BROOM.

41,796.

Specification for Design. Patented Sept. 19, 1911.

Application filed April 10, 1911. Serial No. 620,235. Term of patent 7 years.

To all whom it may concern:

Be it known that I, JOHN FRITZ, a citizen of the United States, residing at Buffalo, in the county of Erie and State of New York, have invented a new, original, and ornamental Design for Brooms, of which the following is a specification, reference being had to the accompanying drawings, forming part thereof.

Figure 1 is a side elevation of a broom

showing my new design. Fig. 2 is a top plan view thereof.

I claim:

The ornamental design for a broom, as shown.

JOHN FRITZ.

Witnesses:

THEO. L. POPP,
ANNA HEIGIS.
